OF FALL RIVER, MASSACHUSETTS.

SAFETY DEVICE FOR PLAYER-PIANOS.

1,068,167.

Specification of Letters Patent.

Patented July 22, 1913.

Application filed October 20, 1911. Serial No. 655,780.

To all whom it may concern:

Be it known that I, ERIC R. PHILBLADE, a citizen of the United States, residing in Fall River, county of Bristol, and State of Massachusetts, have invented an Improvement in Safety Devices for Player-Pianos, of which the following description, in connection with the accompanying drawings, is a specification, like letters on the drawings representing like parts.

This invention relates to a player piano or like instrument in which the player action is operated by power, and has for its object to provide a safety device for preventing injury to the player action or its operating motor.

The safety device referred to is preferably made in the form of a valve, which governs communication between the air feeder or main bellows operated by the motor and the air reservoir with which the player action is connected, and which is normally closed to cut off circulation of air from one to the other, but which is automatically opened when a predetermined or excessive vacuum is formed in the reservoir, to enable the motor to continue to operate the main bellows and circulate air from one to the other. Provision is made for regulating the opening of the valve according to the vacuum at which it is desired the valve should be opened. These and other features of this invention will be pointed out in the claims at the end of this specification.

Figure 1 is a front elevation of a sufficient portion of a player piano embodying this invention to enable it to be understood. Fig. 2, a detail in plan to be referred to. Fig. 3, a vertical section on an enlarged scale taken on the line 3-3, Fig. 2. Fig. 4, a view like Fig. 3 with the parts thereof in a different position, and Fig. 5, a section on the irregular line 5-5, Fig. 3.

Referring to the drawing, *a* represents a main bellows or air feeder, which has its movable member *b* operated by power, and in the present instance operated by an electric motor *c* which is connected with a shaft *d* so as to rotate the same, said shaft having as herein shown a large pulley *e*, which is connected by a belt *f* with a small pulley *g* on the armature shaft of the motor.

The shaft *d* is connected with a crank shaft 10 supported in suitable bearings 12, 13, said shaft in the present instance having

a sprocket wheel 14 which is connected by a link chain 15 to a sprocket wheel 16 on the crank shaft. In the present instance, the crank shaft 10 is connected with the movable members *b* of a plurality of bellows *a*, each of said movable members having fast to it a depending arm 17 which is joined by a connecting rod 18 to a crank 19 on the crank shaft 10. The cranks 19 may be set so that the movable members *b* are operated in succession.

The stationary member 20 of each bellows is secured to one side wall of a wind chest or trunk 21, which is connected with the pneumatic action of the player piano by the tube or pipe 120 indicated by dotted lines in Fig. 1, and is provided as herein shown with a longitudinally extended partition 22 forming two channels or chambers 23, 24, in said wind chest or trunk. The opposite side wall of the wind chest has secured to it the stationary member 25 of a bellows 26 which constitutes an air reservoir and is provided with a movable member 27. The stationary wall 20 of each of the bellows *a* is provided with a port or opening 30, which communicates with the chamber 24, and is normally closed by a valve 31, which is represented as a flap valve and opens into the chamber 24. The wall 20 is also provided with a second port or opening 32 which communicates with the chamber 23 and is normally closed by a valve 33 which opens into the bellows *a*.

The movable member *b* of the bellows *a* is provided with preferably a plurality of ports 35 normally closed to the atmosphere by a valve 36 opening outwardly. The stationary wall 25 of the reservoir 26 is provided with a port 28 communicating with the chamber 23.

In the operation of the apparatus thus far described, the electric motor *c* rotates the crank shaft 10 and through the rod 18 and arm 17 oscillates the movable member *b* of each bellows *a*. On the outward movement of the member *b* in the direction indicated by the arrow 40, Fig. 3, air is drawn from the reservoir 26 through the port 28 into the chamber 23 and through the port 32 into the bellows *a*, the valve 33 being automatically opened. During this movement of the member *b* the valve 31 is closed. A vacuum is thus produced in the reservoir 26, which if allowed to become excessive is liable to cause the cranks and their connecting rods 116

or other part of the motor mechanism to be broken, especially with a continuously running motor.

To prevent injury to the motor mechanism and other operating parts, a safety device is provided which becomes operative when the vacuum in the air reservoir reaches a predetermined point. In the present instance, I have shown one form of safety device, which consists of a valve 43 located in the air reservoir and controlling a port 44 leading from the reservoir into the chamber 24. The valve 43 is shown as fast to a lever 45 pivoted at 46 to a projection 47 on the stationary member or wall 25 of the air reservoir, and having an arm 48 which is extended into the path of movement of the movable member 27 of the air reservoir, and preferably into the path of an adjustable device, shown as a screw 49 extended through said movable wall. The screw 49 is adjusted to be brought into engagement with the arm 48 of the lever 45, when the vacuum in the reservoir reaches a predetermined point, at which time the said lever is turned on its pivot so as to open the valve 43 and thereby afford opportunity for the air drawn out of the reservoir through the ports 28, 32, into the bellows *a* on the movement of the members *b* in the direction of the arrow 40, to be forced back into the reservoir through the ports 30, 44, on the inward movement of the members *b* in the direction opposite to that indicated by the arrow 40. In this manner, an abnormal or excessive vacuum is prevented from being formed in the air reservoir, for as soon as the predetermined vacuum is formed, circulation is established between the bellows *a* and reservoir 26, and the motor can continue to operate without danger of being injured, because the air drawn out of the reservoir into the bellows through the ports 28, 33 is returned to the reservoir through the ports 30, 44. When, however, the vacuum in the air reservoir again falls below the predetermined point, the movable member 27 is moved outwardly, and the screw 49 is withdrawn from contact with the lever arm 48, thereby allowing the valve 43 to be closed by a spring 50 or otherwise, whereupon the circulation of air is interrupted and the air drawn from the reservoir is discharged into the chamber 24 through the port 30 and into the atmosphere through the ports 35.

I may prefer to make the safety device as a valve controlling the circulation of air from the reservoir into the bellows and back into the reservoir, as by so doing a constantly or continuously operating motor mechanism of any kind may be used, but it is not desired to limit the invention in this respect, as I believe myself to be the first to provide a safety device which becomes effective when the vacuum in the air reservoir

reaches a predetermined point. Access to the valve 43 may be had through an opening 53 in the movable member 27 of the air reservoir, which opening is normally closed by a cover 54.

Claims.

1. In an apparatus of the character described, in combination, a wind chest provided with separate chambers, a bellows having its stationary member secured to one side wall of said wind chest and provided with ports connecting said bellows with said chambers, valves controlling said ports, a motor mechanism connected with said bellows to operate it, an air reservoir having its stationary member secured to the opposite side wall of said wind chest and provided with ports connecting said reservoir with said chambers, a valve within said air reservoir normally closing one of the ports in the stationary member of said reservoir, a lever carrying said valve, a spring acting on said lever to normally hold the valve carried thereby in its closed position, and an adjustable device carried by the movable member of said reservoir and co-operating with said lever to open the valve carried by said lever when the vacuum produced in the air reservoir reaches a predetermined point, substantially as described. 95

2. In an apparatus of the character described, in combination, a wind chest provided with separate chambers, a bellows having its stationary member secured to one side wall of said wind chest and provided with ports connecting said bellows with said chambers, valves controlling said ports, a motor mechanism connected with said bellows to operate it, an air reservoir having its stationary member secured to the opposite side wall of said wind chest and provided with ports connecting said reservoir with said chambers, and a valve within said air reservoir normally closing one of the ports in the stationary member of said reservoir and actuated by the movable member of said reservoir to open it and establish a circuit for the air through the said bellows and reservoir, substantially as described. 110

3. In an apparatus of the character described, in combination, a bellows, a motor mechanism to operate it, an air reservoir in communication with said bellows and provided with a movable member, a wind chest having separate chambers connected with said bellows and reservoir and a valve within said reservoir controlling a circuit for the air from the bellows through the wind chest into said reservoir and normally closed, said valve co-operating with the movable member of the said reservoir to be opened thereby to establish the circuit for the air, substantially as described. 125

4. In an apparatus of the character de-

scribed, in combination, a bellows, an air reservoir in communication with said bellows and provided with a movable member, and a valve controlling a circuit for the air 5 from the bellows into the reservoir, said valve being closed when the vacuum within the air reservoir is below a predetermined point and opened by the movable member of the reservoir when the said vacuum 10 reaches said predetermined point.

5. In an apparatus of the character described, in combination, a bellows, a continuously operating motor mechanism connected with said bellows to operate it, an 15 air reservoir communicating with said bellows for the production of a vacuum there-

in by said bellows, a safety device for said motor mechanism, and means whereby said device is rendered effective when a predetermined vacuum is produced in said reservoir, to cause the motor mechanism to effect 20 a circulation of air through said bellows and reservoir without substantially increasing said vacuum, for the purpose specified.

In testimony whereof, I have signed my 25 name to this specification in the presence of two subscribing witnesses.
